UNITED STATES PATENT OFFICE.

BERNHARD BUDWEISER, OF CHICAGO, ILLINOIS.

DESIGN FOR A HELMET.

52,781.

Specification for Design.

Patented Dec. 24, 1918.

Application filed February 9, 1918. Serial No. 216,357. Term of patent 14 years.

To all whom it may concern:

Be it known that I, BERNHARD BUDWEISER, a citizen of the United States, residing at Chicago, in the county of Cook and State of Illinois, have invented a new, original, and ornamental Design for Helmets, of which the following is a specification, reference being had to the accompanying drawing, forming part thereof.

Copies of this patent may be obtained for five cents each, by addressing the "Commissioner of Patents, Washington, D. C."

Fig. 2 shows a side elevation of the article.

What I claim is:

The ornamental design for a helmet, as shown.

BERNHARD BUDWEISER
